B. JOHANSON

JAR GRIPPING LIFTER

Filed April 18, 1922

INVENTOR.

B. JOHANSON

BY *Joseph J. O'Brien*

ATTORNEY.

UNITED STATES PATENT OFFICE.

BERGER JOHANSON, OF SPRINGFIELD, MASSACHUSETTS.

JAR-GRIPPING LIFTER.

Application filed April 18, 1922. Serial No. 555,485.

To all whom it may concern:

Be it known that BERGER JOHANSON, citizen of the United States of America, residing at Springfield, in the county of Hampden and State of Massachusetts, has invented 5 certain new and useful Improvements in Jar-Gripping Lifters, of which the following is a specification.

This invention relates to improvements in 10 lifters for fruit and vegetable jars and its leading object is to provide a device which can be used to grip and lift a jar from a hot water bath, or otherwise, without danger of scalding or burning the hands of the operator, and without danger of crushing the 15 neck of the jar, the device being provided with means for limiting the closing thrust upon the jaws and for minimizing the pressure when contact with the jar neck is established between the jaws and the jar neck. 20

With the above and other objects in view the invention consists in certain new and useful constructions, combinations and arrangements of parts, clearly described in the following specification and fully illustrated in the accompanying drawings, in which:—

The figure is a side elevation.

Referring to the accompanying drawings A designates one of the levers of the device 30 and B the other lever. The two levers are pivotally connected together by means of the rivet C, so as to provide relatively long handles D and E. Each of the levers is formed at its forward end with a substantially L-shaped jaw F. Each lever is preferably formed of flat strip stock and the forward end portion providing the jaw F is twisted upon the shank of the handle forwardly of the pivot, the twist being substantially one-quarter of a turn, or about 90 degrees. By this arrangement the flat sides of the stock extending along the jaws confront each other. 40

The lever B is deflected at the point of the 45 twist b thereof, so as to provide a sloping or inclined stop G, which is engaged by the edge portion H of the lever A, and which not only provides means for limiting the closing

action of the jaws toward each other upon the neck of the jar to be handled, but which also provides means for reducing the actual pressure exerted upon the neck of the glass jar. After the edge portion H engages the sloping stop G a slight movement of the jaws toward each other is permitted, as continued pressure upon the handles will force the edge portion H along the sloping stop G, against the lateral tension or resistance offered by the stock of the metal. 50

By this arrangement it is impossible to 60 apply a crushing pressure on the heated neck of a glass jar, so that the device is designed in such manner as to protect the fruit and vegetable jars against destruction due to a sudden application of gripping pressure 65 upon opposite sides of the jar neck.

The terminal portions of each of the jaws is equipped with a curved jaw piece I, designed to fit the jar neck. This piece I may be secured by a rivet or welding, or 70 other like fastening means, or may be secured pivotally, as shown in dotted lines, so that the device may be employed for handling jars by placing the device at right angles thereto, instead of over the jar, as 75 is required in most cases.

Having described my invention I claim and desire to secure by Letters Patent:—

A jar gripping lifter, comprising a pair of levers, each lever having a handle and an L-shaped forward portion having a jar gripping jaw each lever being made from bar material having flat inner sides, the handles being pivoted to each other rearwardly of the L-shaped portions thereof, each L-shaped portion being connected to its handle by a twisted portion providing an inwardly deflected edge, the deflected edges facing each other and being adapted to abut against each other to limit the closing thrust of the L-shaped portions on each other, whereby the pressure exerted on a jar by the closing of said jaws upon it will be limited by the abutment of said deflected edges. 80 85 90

Signed by me at Springfield, Mass.

BERGER JOHANSON.
